UNITED STATES PATENT OFFICE.

RUDOLPH C. LOESER, OF LOUISVILLE, KENTUCKY, ASSIGNOR TO PEERLESS MANUFACTURING CO., OF DOVER, DELAWARE, A CORPORATION OF DELAWARE.

DESIGN FOR A RADIANT GAS HEATER.

Application filed March 9, 1929. Serial No. 30,408. Term of patent 3½ years.

To all whom it may concern:

Be it known that I, RUDOLPH C. LOESER, a citizen of the United States, and a resident of Louisville, county of Jefferson, and State of Kentucky, have invented a new, original, and ornamental Design for Radiant Gas Heater, of which the following is a specification, reference being had to the accompanying drawing, forming a part thereof.

The figure is a perspective front elevational view of the radiant gas heater, showing my new design, the heater being of conventional depth.

I claim:

The ornamental design for a radiant gas heater, as shown and described.

In testimony whereof I affix my signature.

RUDOLPH C. LOESER.
